UNITED STATES PATENT OFFICE

BENJAMIN G. CASLER, OF TONAWANDA, NEW YORK, ASSIGNOR OF ONE-THIRD TO
FREDERIC W. RITTER, JR., OF WASHINGTON, DISTRICT OF COLUMBIA, AND ONE-
SIXTH TO JOHN AYRAULT AND ONE-SIXTH TO MILES AYRAULT, BOTH OF TONA-
WANDA, NEW YORK.

REELING AND WRAPPING MACHINE.

1,144,348.

Specification of Letters Patent. Patented June 29, 1915.

Application filed November 7, 1914. Serial No. 370,308.

To all whom it may concern:

Be it known that I, BENJAMIN G. CASLER, a citizen of the United States, residing at Tonawanda, in the county of Erie and State 5 of New York, have invented certain new and useful Improvements in Reeling and Wrapping Machines; and I do hereby declare the following to be a full, clear, and exact description of the invention, such as will enable others skilled in the art to which it 10 appertains to make and use the same.

My invention, broadly stated, relates to that class of devices employed for reeling and wrapping fabrics, but has been especially devised for handling ready roofing fabrics directly from the delivery or conveyor belt of a ready roofing machine, the reeling of the ready roofing fabric, the applying of the wrapper to the roll of ready 15 roofing fabric, and the delivery of the roll so wrapped on the floor of the shop, ready for end capping and shipment, at a great reduction in the number of laborers employed therefor, and in the time and labor 20 required, and at a consequent great reduction in the cost of manufacturing and marketing ready roofing fabrics.

To this end my invention, generally stated, involves, in combination, a plurality of revolving reel-heads which are relatively movable to and from each other to engage the ends of a mandrel, mandrel delivering devices so arranged with relation to the revolving reel-heads as to deliver a mandrel 25 between and in relation to the axes of said revolving heads, and means for controlling the delivery of the mandrels between the revolving heads, whereby a mandrel therefor is automatically presented in the path of the 30 ready roofing fabric as it comes from the ready roofing fabric machine.

My invention also involves the combination with a plurality of revolving reel-heads which are relatively movable to and from 45 each other to engage the ends of a mandrel, and mandrel delivering devices so arranged with relation to the revolving heads as to deliver a mandrel between and in axial relation to said revolving reel-heads, of a wrap- 50 per receptacle, and means interposed between the wrapper receptacle and the revolving adjustable heads for applying ad-

hesive material to the wrapper on its way to the roll of ready roofing fabric.

My invention also involves the combination with a plurality of revolving reel-heads movable to and from each other to engage the ends of a mandrel, and mandrel delivering devices so arranged with relation to the revolving reel-heads as to deliver a mandrel 55 between and in axial relation to said revolving reel-heads, of a carrier adapted to move to and from the revolving reel-heads to receive and remove the roll of roofing fabric when the reeling thereof has been completed. 60

There are other features of invention involving particular combinations of elements, and particular features of elemental construction, all as will hereinafter more fully 65 appear.

In the drawings chosen for the purpose of illustrating my invention, the scope whereof is pointed out in the claims,

Figure 1 is a view in front elevation of a 75 reeling and wrapping machine embodying my invention, portions of the mandrel delivering devices being broken off; Fig. 2 is a vertical transverse sectional view of the reeling, wrapping, and mandrel delivering 80 devices taken in the plane of the line 2—2, Fig. 1; Fig. 3 is a detail view showing the relation of the delivery end of the belt conveyor of a ready roofing fabric machine, a mandrel in the reeling machine, and the 85 ready roofing fabric to be reeled up; Fig. 4 is a detail sectional view of portions of the reeling and wrapping machine showing the application of the wrapper to the roll of ready roofing fabric; and Fig. 5 is a horizontal sectional view of the mandrel delivering 90 devices taken in the plane of the line 5—5, Fig. 2.

Like symbols refer to like parts wherever they occur. 95

I will now proceed to describe my invention more fully so that others skilled in the art to which it appertains may apply the same.

In the drawings, A indicates the uprights 100 or supports, and α the bed thereon, which, or a like suitable support for the operative reeling and wrapping elements of the machine will be provided. The mandrel delivering

devices may be supported from bed *a* by brackets (not shown), or by suitable separate supports.

Journaled in suitable pillow blocks 1, at 5 opposite ends of the bed *a*, and in axial alinement, are revolving shafts 2, each of which is adapted to have an endwise movement toward and from the other, and in order to effect and control said endwise 10 movement of shafts 2, levers 3, fulcrumed on the opposite ends of bed *a*, are pivotally connected as at 3^a to collars 2^a loose on the shafts 2. The shafts are capable of rotation within the loose collars 2^a, but the endwise 15 movement of the collars on the shafts 2 is prevented by other collars 2^b which are secured to said shafts 2.

The levers 3 are offset below where they are fulcrumed on bed *a*, as indicated in 20 dotted lines Fig. 4, in order to carry toward the front of the machine the rods 4 by which levers 3 are operated to allow of clearance for the passage of the wrappers with which the fabric roll is to be covered.

25 The rods 4, which are pivotally connected at one end with the lower ends of the opposite levers 3, are at their other ends pivotally connected with the opposite ends of a rock-lever 5, which rock-lever 5 is in turn pivoted 30 as at 5^a on a cross-bar 6 secured to the frame of the machine at the front and below bed *a*.

Rock-lever 5 has two horizontally extending arms one of which carries a counterweight 7 and the other of which is provided 35 with a handle 8. This last named arm of the lever engages a stop 7^a on the cross-bar 6 when it is desired to prevent the action of the counterweight 7 on the rock-lever 5.

9 indicates a power shaft suitably journaled on the frame A below bed *a*. This shaft is provided with a pulley 9^a through which it receives its power and is rotated by a suitable belt, and it is also provided with pulleys 9^b, 9^c by which it, through 40 belts 10 and 11 and pulleys 12 and 13, communicates the power which causes the rotation of shafts 2, and the reel-heads thereon.

The connections between the pulleys 12 and 13 and the shafts 2, are of the usual feather 45 or spline and groove character which, while they cause the shafts to rotate with the pulleys permit an endwise movement of the shafts through the pulleys.

On the adjacent ends of shafts 2, are secured 50 reel-heads 14 adapted to engage the opposite ends of a mandrel, and to insure the grip of the heads on the mandrel it is preferred to cone the heads slightly as at 14^a and encircle the coned portions of the head 55 with a serrated annulus as at 14^b.

Above the rotating reel-heads 14 is located a chute 15 for containing mandrels which are to be fed at intervals between the rotating heads 14. This chute, the outlet of 60 which is above the axis of rotation of the

reel-heads 14, can be supported from brackets on the bed *a* (not shown), or in any other suitable manner.

On rearwardly projecting arms or brackets 65 16 is pivoted a counterweighted oscillating frame 17 having for its object the reception of a mandrel from the chute 15 and its delivery between the revolving heads 14, and in order that this frame 17 after having delivered a mandrel to the reel-heads 14 70 75 may clear the mandrel on its return movement, the carrying portion 17^a of said frame 17 is pivoted thereto as at 17^b. When acting as a carrier said portion is held in alinement with the body portion of frame 17 by 80 a dog 18.

In order that the pivoted carrier portion 17^a of the frame shall be returned to alinement with the main body 17 the frame at the close of the upward or return movement 85 thereof said pivoted carrier portion 17^a of the delivery frame is provided with a lug or projection 17^c which sets at an angle to the carrier portion 17^a and engages a downwardly projecting stop 19 on the lower end 90 of mandrel chute 15.

It is to be noted that whatever may be the character of the devices chosen for delivering the mandrel to the reel-heads they must be so located and operated as to avoid obstructing the path of the fabric from the conveyor belt C to the reel-heads 14. 95

To control the delivery of the mandrels, I employ a spring-actuated cut-off 15^d, comprised of two connected blades, 15^b and 15^c, 100 which are arranged to alternately project into the mandrel chute 15 through slots in the front and back walls of the chute, said blades and slots being spaced apart a distance equal to the diameter of a mandrel. 105 The normal position of the lower blade 15^b is in the chute, while that of the upper blade 15^c is outside the chute. The position of the blades is reversed by means of the handle 15^d when a mandrel is to be fed down to the 110 mandrel delivery frame 17.

On the bed which supports the pillow blocks 1 below and adjacent to the revolving heads 14, are inclined ways 20 for the reception of the roll of ready roofing fabric when 115 released from the revolving heads 14, and for the delivery of the roll to an oscillating roll carrier 23, which receives the roll and delivers it upon the floor of the shop at one end of the reeling and wrapping machine. 120

These ways 20 are transversely slotted as at 20^a (see Figs. 1 and 4) for the passage and guidance of the roll wrapper, and in order to facilitate the entrance of the wrapper into said guides the walls of slots 20^a 125 diverge downwardly as indicated in Fig. 2 of the drawings.

Below the bed *a* of the machine, back of and parallel with the guide slots 20^a, is a trough 21 for paste or equivalent adhesive 130

material, and in said trough is a feed roller 21^a which delivers the adhesive material to a pasting roller 21^b that applies the adhesive matter to the wrapper. Beneath the paste trough 21 is an inclined wrapper receptacle 22 the upper end of which is below and substantially in line with the guide slots 20^a of the ways 20, and opposite to the pasting roller 21^b is a swinging roller 21^c controlled by a handle 21^d by means of which said roller 21^c, that normally stands out of the path of the wrapper, may be operated to press the wrapper against the pasting roller 21^b.

15 To maintain the wrapper W in proper position in wrapper receptacle 22 a leaf spring 22^a, or its equivalent, may be employed.

In front of the reeling and wrapping machine is placed a roll carrier 23 supported by a stem 23^a pivoted at its lower end on the floor of the shop, or otherwise suitably arranged, so that the roll carrier may be caused to oscillate across the front of bed *a* in juxtaposition to the lower ends of inclined ways 20, to receive and deliver the roll, and also so that it may be turned aside to be out of the way when the reel is forming the roll.

C indicates the delivery apron, or conveyer belt, which delivers the ready roofing fabric from the ready roofing fabric machine to the reeling and wrapping machine, and *m* indicates the mandrel on which the ready roofing fabric is to be reeled.

The delivery end of the conveyer belt or apron C is parallel with the axis of rotation of the reel heads to insure the proper delivery of the fabric to be wound on the mandrel when in position between the reel-heads, and is preferably below the axis of rotation of the reel-heads to insure that the fabric shall be kept taut during the reeling operation. A mandrel having a peripheral flap *f* (see Fig. 3) is preferably used in order to loosely entrap the leading end of the ready roofing sheet F. The subsequent labeling of the roll may be avoided, and time and labor saved by printing the label on the wrapper before the wrappers are stacked in the wrapper receptacle 22 of the machine.

50 The construction of the machine being substantially such as hereinbefore pointed out, its operation will be as follows: The chute 15 having been charged with mandrels *m*, the operator who stands in front of the machine will first manipulate the handle 15^a of the cut-off to force in the upper cut-off blade 15^c and retract the lower cut-off blade 15^b which prevents the descent of the mandrels above cut-off blade 15^c, and permits the mandrel below said cut-off blade to drop into the position, indicated in dotted lines Fig. 2, on the mandrel carrier 17. The pushing in of the cut-off blade 15^c energizes the spring of the cut-off frame and its reaction, 65 when handle 15^a is released, returns blades

15^b and 15^c to their normal positions, shown in Fig. 2 of the drawing, the stack of mandrels having dropped the diameter of one mandrel and again come to a rest on cut-off blade 15^b. The mandrel which has been released and fallen on the counterweighted mandrel carrier 17 overbalances the counterweight of the frame and that end of the mandrel carrier on which the mandrel rests descends until the mandrel carried thereby is between the reel-heads 14 and in axial alinement therewith, whereupon the operator by means of handle 8 releases the rock-shaft 5 from catch 7^a and the descent of weight 7 acting through rock-shaft 5, rods 4, and pivoted levers 3 on shafts 2 forces the reel-heads 14 toward each other and in gripping contact with the ends of the mandrel. The weight 7 will determine the power of the grip or pressure on the ends of the mandrel, and may be controlled at will by either changing the weight or slidingly connecting the weight to the arm of the rock-lever. The operator then trips the dog 18 which releases the hinged carrier portion 17^a of carrier frame 17, and it drops into the position indicated in dotted lines Fig. 2 of the drawings, and this permits the carrier frame to clear the mandrel held by reel-heads 14 as the frame 17 rises under the action of its counterweight. When the frame 17 has risen to its normal position under the chute 15, the lug 17^c on pivoted portion 17^a of the frame strikes the projection 19 and causes the dog 18 to again lock the pivoted carrier portion 17^a in alinement with the main portion 17 of the carrier frame. The operator now taking hold of the leading end of the sheet of roofing fabric to be reeled as it comes from the conveyer belt C, guides it to the mandrel and under the peripheral flap thereof—if the mandrel has a flap. If the machine is then at rest the operator applies the power to driving shaft 9 by moving the usual clutch lever 100 and clutch (not shown) and through the intermediary pulleys and belts the shafts 2 and reel-heads 14 together with the mandrel are caused to rotate and reel the sheet of roofing fabric on the mandrel. On the completion of the roll the operator reaching down through the open center of table *a* grasps the leading end of a wrapper W, in wrapper receptacle 22, and draws the wrapper up into guide slots 20^a in ways 20, inserting the leading end of the wrapper under the free end of the rolled fabric, whereupon the continued rotation of the roll of fabric will cause the wrapper, controlled by the guide slots 20^a, to apply itself evenly 115 and uniformly to the roll of ready roofing fabric. As the last portion of the wrapper is passing the pasting roller 21^b the operator manipulates handle 21^d of swinging roller 21^c to cause said roller to force the

passing wrapper in contact with pasting roll 21^b which applies the adhesive material to the wrapper, and thereafter, if desired, a hand tool may be applied by the operator to the revolving wrapped roll of fabric to insure the adhesion of the pasted portion of the wrapper on the roll.

The wrapped roll being now ready for removal from the reeling and wrapping machine, the roll carrier 23, which has, in the meantime, occupied the position at one end of the machine, as indicated in Fig. 1 of the drawings, is raised into position parallel with bed *a* of the machine and in juxtaposition to the ends of inclined ways 20, the power is thrown off of the machine, handle 8 of rock-lever 5 is manipulated to lift weight 7 and bring the rock-shaft 5 into the vertical position, shown in Fig. 1 of the drawings, with the handle arm under catch 7^a. This operation acting through rods 4 and levers 3 withdraws shafts 2 and reel-heads 14, which permits the wrapped roll to drop on the inclined ways 20, whence it rolls into roll carrier 23, and the roll carrier being turned down into the position shown in Fig. 1 of the drawing delivers the wrapped roll on the floor of the workshop at one side of the machine.

As the invention hereinbefore set forth is applicable, without further invention, to reeling and wrapping fabrics in general, the claims hereinafter made are not to be construed as limited to the reeling and wrapping of ready roofing fabrics which has been chosen only as illustrating a particular field of usefulness.

Having thus described my invention what I claim and desire to secure by Letters Patent is:

1. In a machine for reeling fabrics; the combination of a plurality of revoluble reel-heads, said heads being relatively movable to and from each other, a chute for containing mandrels, a mandrel carrier having a portion which is adapted to receive a mandrel and transfer the same to a position in axial alinement with the reel-heads for the reception of the fabric to be wound thereon, said mandrel carrier being movable independently of the mandrel-chute and the mandrel receiving portion of the carrier arranged to describe an arc which intersects the axis of rotation of the reel heads.

2. In a machine for reeling and wrapping ready roofing fabrics, the combination of a plurality of revoluble reel-heads, said reel-heads being relatively movable to and from each other, means for delivering a mandrel between said reel-heads and in axial relation thereto, in position to receive the fabric to be wound thereon, a wrapper receptacle, and means for applying adhesive material to a wrapper, said last-recited

means being interposed between the wrapper receptacle and the revoluble reel-heads.

3. In a machine for reeling and wrapping ready roofing fabrics, the combination of a plurality of revoluble reel-heads, said reel-heads being relatively movable to and from each other, means for delivering a mandrel between and in axial relation to said reel-heads in position to receive the fabric to be wound thereon, and an oscillating roll carrier, said roll carrier being movable across the front of the machine and in juxtaposition thereto to receive the roll from the reel-heads and deliver it at one side of the machine.

4. In a machine for reeling and wrapping ready roofing fabrics, the combination of a plurality of revoluble reel-heads, said reel-heads being relatively movable to and from each other, means for delivering a mandrel between and in axial relation to said reel-heads in position to receive the fabric to be wound thereon, a wrapper receptacle, means interposed between the wrapper receptacle and the revoluble reel-heads for applying adhesive material to a wrapper, and a roll carrier said roll carrier being movable to and from the revoluble reel-heads to receive and deliver a finished roll.

5. In a machine for reeling and wrapping ready roofing fabrics, the combination of a plurality of revoluble reel-heads, said reel-heads relatively movable to and from each other, a mandrel chute, and a counterweighted mandrel carrier interposed between the mandrel chute and the revoluble reel-heads, said mandrel carrier being movable independently of the mandrel chute for delivering a mandrel between and in axial relation to the revoluble reel-heads.

6. In a machine for reeling and wrapping ready roofing fabrics, the combination of a plurality of revoluble reel-heads, said reel-heads relatively movable to and from each other, a mandrel chute, a counterweighted mandrel carrier for delivering a mandrel between and in axial relation to said removable head, said mandrel-carrier having a pivoted portion, and means for securing and releasing the pivoted portion of the mandrel carrier.

7. In a machine for reeling and wrapping ready roofing fabrics, the combination of a plurality of axially alined revoluble shafts, said shafts being relatively movable longitudinally to and from each other, reel-heads on the adjacent ends of said shafts, counterweighted means for causing the longitudinal movement of said shafts toward each other, and means for delivering a mandrel between and in axial relation to said reel-heads.

8. In a machine for reeling and wrapping ready roofing fabrics, the combination of a

- plurality of revolute reel-heads, said reel-heads being relatively movable to and from each other, a mandrel chute, a cut-off on the mandrel chute for controlling the delivery 5 of a mandrel, and a counterweighted mandrel carrier interposed between the chute and the revolute reel-heads for delivering a mandrel to the revolute reel-heads.
9. In a machine for reeling and wrapping 10 ready roofing fabrics, the combination of a plurality of revolute reel-heads, said reel-heads being relatively movable to and from each other, means for delivering a mandrel between and in axial relation to said reel-heads, inclined ways located below and adjacent to said revolute reel-heads, and a roll carrier, said roll carrier being movable to and from the revolute reel-heads in juxtaposition to the delivery ends of said inclined ways.
10. In a machine for reeling and wrapping ready roofing fabrics, the combination of a plurality of revolute reel-heads, said reel-heads being relatively movable to and from each other, means for delivering a mandrel between and in axial relation to said reel-heads in position to receive the fabric to be wound thereon, a wrapper receptacle, means interposed between the wrapper receptacle 25 and the reel-heads for applying adhesive material to a wrapper, a roll carrier, ways interposed between the reel-heads and the roll carrier, said ways having slots constituting wrapper guides.
11. In a machine for reeling fabrics, the combination of a plurality of revolute reel-heads, said reel-heads being relatively movable to and from each other, a mandrel chute, a spring-actuated mandrel support 30 and cut-off for the mandrel chute, and means movable independently of the mandrel chute for delivering a mandrel between and in axial relation to the reel-heads.
12. In a machine for reeling fabrics, the combination of a plurality of revolute reel-heads, said reel-heads being relatively movable to and from each other, a mandrel chute, a spring-actuated mandrel support 35 and cut-off for the mandrel chute, and oscillating means for delivering a mandrel between and in axial relation to the reel-heads, said mandrel delivering means being movable independently of the mandrel chute.
13. In a machine for reeling fabrics, the combination of a plurality of revolute reel-heads, said reel-heads being relatively movable to and from each other, a mandrel chute, a spring-actuated mandrel support 40 and cut-off for the mandrel chute, and a counterweighted oscillating means for delivering a mandrel between and in axial re-
- lation to the reel-heads, said mandrel delivering means being movable independently of the mandrel chute.
14. In a machine for reeling fabrics, the 65 combination of a plurality of revolute reel-heads, said heads being relatively movable to and from each other, means for delivering a mandrel between and in axial relation to the reel-heads, an oscillating roll-carrier, 70 and ways interposed between the reel-heads and the roll carrier.
15. In a machine for reeling and wrapping fabrics, the combination of a plurality of revolute reel-heads, said reel-heads being 75 relatively movable to and from each other, means for delivering a mandrel between and in axial relation to the reel-heads in position to receive the fabric to be wound thereon, a wrapper receptacle, a roll carrier, said roll 80 carrier being movable to and from the reel-heads, and ways interposed between the reel-heads and the roll carrier, said ways having wrapper guides.
16. In a machine for reeling fabrics, the 85 combination of a mandrel chute, a plurality of revolute reel-heads, said reel heads being relatively movable to and from each other, the axis of rotation of the reel-heads being below the outlet of the mandrel chute, and 90 means for delivering a mandrel between and in axial relation to the reel-heads, said mandrel delivering means being movable independently of the mandrel chute.
17. In a machine for reeling fabrics, the 95 combination of a plurality of revolute reel-heads, said reel-heads being relatively movable to and from each other, a mandrel chute the outlet thereof being located above the axis of rotation of the reel-heads, means for 100 delivering a mandrel between and in axial relation to said reel-heads, and a conveyer belt the delivery end of said conveyer belt being parallel with the axis of rotation of the reel heads. 105
18. In a machine for reeling fabrics, the combination of a plurality of revolute reel-heads, said reel-heads being relatively movable to and from each other, a mandrel chute the outlet thereof being located above the 110 axis of rotation of the reel-heads, means for delivering a mandrel between and in axial relation to the reel-heads, and a conveyer belt the upper surface whereof is below the axis of rotation of the reel-heads. 115
